Edwin L. Smalley Inventor
By his Attorney, J. W. Miller

UNITED STATES PATENT OFFICE.

EDWIN L. SMALLEY, OF EAST ORANGE, NEW JERSEY.

SECTIONAL ELECTRIC FURNACE.

Application filed August 6, 1920. Serial No. 401,718.

To all whom it may concern:

Be it known that I, EDWIN L. SMALLEY, a citizen of the United States, and resident of East Orange, in the county of Essex and State of New Jersey, have invented certain new and useful Improvements in Sectional Electric Furnaces, of which the following is a specification.

This invention relates to electric furnaces of the same general character as that disclosed in my earlier Patent No. 1,346,854, which is directed particularly to multiple-replaceable-unit furnaces of size and capacity suited for industrial uses and my present improvements are directed to such furnaces whose great length has created a difficulty in the renewal of individual portions thereof, as by damage to a unit refractory, or the burning out of a heating unit or coil.

Therefore my invention consists in the production of large size furnaces in longitudinal sections, composed each of housing bricks of pressed infusorial earth or other suitable material that is non-conductive of electricity, comprising a housing, which is in turn encased in a metallic shell. These sections, which contain, interiorly of the brick housing thereof, heating units which may be supported therein as by unit refractories, or otherwise, are arranged in endwise relation, and secured together as by the provision of flanges at the respective ends of the metallic shells and bolting together the opposed flanges of adjacent shells.

Furthermore, each furnace section, thus constituted, is mounted on standards that are each provided with traction means, and spaced rails are provided to form a track for said traction means, so that when the bolts uniting the sections, or any of them, are removed, the released section or sections may be drawn apart. By these means any individual section of the furnace is rendered fully accessible for the purpose of repairing or replacing any component part thereof.

Other features and advantages of my invention will hereinafter appear.

In the drawing:

Figure 1 is a side elevation of an electrical furnace composed of removable sections in connected relation.

Fig. 2 is a side sectional elevation of one

of the furnace sections, in removed relation, and

Fig. 3 is an end view of Fig. 1.

In said views I have shown a furnace composed of a number of endwise opposed sections, which, according to their number and hence the aggregate length accorded the furnace, thereby enables the latter to answer the requirements of certain industrial uses. By means of sectional construction the total length of the furnace is attained by the assemblage of an appropriate number of sections. But it is also necessary, for repair purposes to any particular section, that the means for connection of the sections one to another be simple and convenient to operate, also that suitable means be provided whereby the sections are, when released, readily movable relatively to one another, so that they may be drawn apart and again re-united with the least possible effort.

Therefore my improved furnace, illustrated in Fig. 1, is seen to be composed of a series of longitudinal sections 1, each provided with end flanges 2, whereby the opposed flanges on adjacent sections may be connected as by bolts 3, to thus removably unite the sections.

Each furnace section is shown as provided with individual supporting standards 4, having terminal wheels 5, whereof the wheels for the standards at each side of each section are mounted on a rail 6, a pair of such rails constituting a track for the movable support of the sections, both individually and as in connected, complete furnace form.

The individual furnace sections, as shown in the example of Fig. 2, each comprise a metallic shell or casing element, lined interiorly with a suitable brick housing 7, which may be of pressed infusorial earth, or the like, and each section provided with a heating element, in the form of a resistance conductor, such as indicated at 8, as carried by a muffle which is here shown as composed of units refractories.

The usual practice is followed in connecting up the resistance conductors for the assembled sections to include them in circuit with the source of electrical energy, but is not otherwise referred to herein as forming part of the present invention.

It is to be understood that the rail track

is intended to comprise the base upon which the furnace is to be mounted by means of its traction supports in the installation of the furnace, said track having sufficient length, exceeding the furnace length, to permit the sections to be drawn apart, so that convenient access may be had to the interior of any individual section needing repairs or renewal of parts.

10 It will be noted that the traction means, such as the wheels 5, have inner flanges, to co-act with the rails for the purpose of preventing derailment, and also for maintaining alignment of furnace sections.

15 Variations within the spirit and scope of my invention are equally comprehended herein by virtue of the foregoing disclosure.

I claim:

1. In an electrical furnace, in combination, a plurality of longitudinal furnace sections, composed of non-magnetic material, adapted for removable, endwise engagement, to permit variations in the fur-

nace length, a resistor element common to the sections of the furnace, and individual traction means for the sections. 25

2. In an electrical furnace, in combination, a plurality of longitudinal furnace sections capable of removable, endwise abutting relation, to permit variations in the furnace length, releasable means of engagement for adjacent sections, and individual traction means for the sections. 30

3. In an electrical furnace, in combination, a longitudinal track, a plurality of longitudinal furnace sections adapted for removable, endwise engagement, to permit variations in the furnace length, and individual, aligned traction means for the sections to movably support them on the 35 40 track.

Signed at New York in the county of New York and State of New York this second day of August A. D. 1920.

EDWIN L. SMALLEY.
